UNITED STATES PATENT OFFICE.

FRANK E. BROWN, OF WEBSTER CITY, IOWA.

ROLLER-SKATE.

1,204,541.

Specification of Letters Patent.

Patented Nov. 14, 1916.

Application filed January 28, 1915. Serial No. 4,913.

To all whom it may concern:

Be it known that I, FRANK E. BROWN, a citizen of the United States, residing at Webster City, in the county of Hamilton 5 and State of Iowa, have invented certain new and useful Improvements in Roller-Skates, of which the following is a specification.

An object of my invention is to provide 10 a skate which has the front and back rolls thereof arranged to be extensible, and has a securing structure to hold the adjustable members connected in a manner that while relative movement of the parts is permitted 15 in the adjustment, the parts are secured in an absolutely rigid and immovable relation and against accidental readjustment in use.

A further object is to construct the steering structure of the extension and the parts 20 thereof entirely of sheet metal with the exception of the clamping bolts and to so arrange the members of the same that an interfitting and telescoping connection is formed in which one portion of the structure 25 embraces the remaining portions and in which spreading of the securing structure is prevented.

Yet another object is to provide a skate 30 which is equally well adapted to use of straps as a means of securing the same to the foot, as to a full clamp fastening or a combination of the same.

With other objects in view, which will be referred to, my invention consists in the 35 novel features of construction and combination of parts which will be hereinafter more fully set forth in connection with the accompanying drawings and more particularly pointed out in the appended claims.

40 In the drawings: Figure 1 is a view in side elevation of a form of my improved skate having a clamp fastening for the sole and a strap fastening secured to the heel plate. Fig. 2 is a top plan view of the dis- 45 closure in Fig. 1. Fig. 3 is a transverse vertical sectional view taken on the line 3—3 of Fig. 1 to better illustrate the securing or clamping means of the adjustment mechanism.

50 The wheel trucks or carriages 1 and 2 are of the standard form and design and are pivotally mounted by the pins 3 and 4 and provided with the rubber cushion blocks to permit side swinging of the forward and 55 rear axles 5 and 6 respectively, to allow the

wheels 7 mounted thereon to describe an arc or curved line. The carriages 1 and 2 are mounted by being connected with the toe member 8 and the heel member 9.

A toe plate 10 is secured to the toe member 8 by having slots formed therethrough and the tongues 11 of the side pieces 12 of the toe member pass through these slots and are riveted over, and a heel plate 13 is secured by the rivets 14, or in any other desired manner, to the side plates 15 of the heel member 9 to be disposed in a substantially parallel plane with the toe plate 10. The side plates 12 of the toe member 8 are extended to form the elongated extension 60 bars 16, and similar elongated extension bars 17 are provided to extend forwardly from the side plates 15 of the heel member 9. Upturned flanges 18 and 19 are provided on the lower edges of the extension 65 bars 16 and 17 respectively, and bars 17 are spaced apart to be received between the bars 16 and to have the flanges 19 thereof bear against the lower faces of the flanges 18, this structure being better illustrated in 70 Fig. 3.

Pins 20 are carried by the extension bars 75 17 to project from the inner faces thereof and to come to an abutting relation at their inner ends to prevent springing of the extension portion 17 from the position of bearing against the inner faces of the extension bars 16, and a securing clip 21, which comprises a top having side flanges 80 22 is made of a transverse dimension that 90 the side flanges will fit closely over the extension bars 16 to hold these bars in the proper relation. A clamp bolt 23 is received through an orifice 24 in the top of the clip 21 and passes down between the extension bars 17 where a clamp washer 25 is fitted over the ends to bear against the flanges 19 of the extension bars 17, a nut 26 being received on the screw-threaded end of the bolt 23 to clamp the clip 21 against 95 the top edges of the extension bars 16 and the washer 25 against the lower sides of bars 17 to cause the flanges 18 and 19 to be brought to a frictional bearing and to prevent end movement of the extension members 16 with respect to the members 17. Pins 27 are mounted to project from the outer faces of the extension bars 16 to limit movement of these bars with respect to the clip 21, and it will be noted that the abut- 100 105 110

ment of the pins 20 against the bolt 23 will prevent too great movement of the extension bars 17.

In Figs. 1 and 2, a fastening means adapted for employment upon the skates intended for the use of women and children is disclosed, and in this arrangement, the toe fastening is of the usual clamp form adapted for such change, the clamp members 28 and 29 being simultaneously adjusted and brought to a bearing relation against the sole of the shoe by turning the clamp screw 30 with a wrench or other suitable means. The heel plate 13 has upturned limbs or ears 31 provided around the outer extent thereof and a metal heel band 32 is secured to these ears by rivets 33 to form a rigid structure with the heel plate, a felt, leather, or other protective lining 34 being secured in place within the heel band 32 to protect the heel of the shoe from the wear of the metal. A buckle 35 is secured to one side of the heel band 32 by a metal band 36 which is riveted in place, and a strap or other flexible member 37 is secured to the opposite side of the heel band 32 to be received across the instep of the wearer and to have the tongue of the buckle penetrated through one of the openings 38 thereof to procure the proper tension across the foot.

In the use of the skate and in fitting the same to the foot, the nut 26 on the end of the bolt 23 is loosened to release the bearing tension exerted by the head of the bolt 35 and by the washer 25, and the heel member 9 and the toe member 8 may then be adjusted to bring the forward axle 5 to the proper position beneath the ball of the foot to accomplish the proper poise over the front wheels 7 mounted on the axle. When the desired adjustment has been obtained, the nut 26 will be again tightened against the washer 25 and the head of the bolt 23 will come into bearing engagement with the top of the clip 21 which will cause the side extension 22 thereof to exert a bearing pressure against the flanges 18 of the extension plates 16 and will bring these flanges to a frictional bearing contact against the flanges 19 of the extension plates 17 and will securely clamp the extension plates of the members 8 and 9 in the proper adjusted relation and to be frictionally held against accidental endwise movement which would permit shifting of the forward truck or carriage and the wheels by which the same is supported to an improper adjustment. The strap 37 is then brought across the instep of the foot and the buckle 35 has the tongue passed through one of the openings 38 to hold the shoe properly positioned within the heel band 32. The toe clamp members 28 and 29 are tightened against the side edges of the sole of the shoe in the manner as hereinbefore set forth, and the

skate is positioned and securely held in the proper relation.

From the foregoing, it will be seen that I have provided a skate having heel and toe portions by which the wheel-carrying trucks are held in the proper relation, which members are freely adjustable. Further, it will be seen that the connection between the heel and toe portions of the skate is in the nature of an angle-iron truss structure in which the one member gives support to and receives strength from the remaining members and that there is very little possibility of the extension structure between the members of the skate becoming bent or otherwise disaligned.

While I have herein shown and described only specific forms and adaptations of the invention, it will be understood that slight changes might be made in the form and arrangement of the several parts without departing from the spirit and scope of my invention, and hence I do not wish to be limited thereto except for such limitations as the claims may import.

I claim:

1. A skate comprising heel and toe portions, a pair of spaced-apart extension plates having outwardly extending flanges carried at the lower edges thereof arranged to project from the heel portion in a forward direction, a pair of like flanged plates carried by the toe portion in a spaced-apart relation to be interfitted with the extension plates of the heel portion, and means to bear against said extension plates and the flanges thereof to secure the same in a rigid adjusted relation and to prevent longitudinal shifting of the one pair with respect to the remaining plates.

2. A skate comprising heel and toe portions, a pair of spaced-apart extension plates having outwardly extending flanges provided at the lower edges thereof, which plates are arranged to project from the heel portion in a forward direction, a pair of like flanged plates carried by the toe portion in a spaced-apart relation to be interfitted with the extension plates of the heel portion, a clip to be fitted over the interfitting extension plates, and a clamp bolt co-operating with said clip to bring the plates of the one pair to a frictional bearing against the plates of the second pair and to maintain the heel and toe portions rigidly in their spaced relation.

3. A skate comprising heel and toe portions, a pair of spaced-apart extension plates having outwardly extending flanges carried at one edge thereof formed to project from the heel portion in a forward direction, a pair of like flanged plates carried by the toe portion in a spaced-apart relation to be interfitted with the extension plates of the heel portion, a U-shaped clip

to be fitted over the interfitted extension plates, and a clamp bolt coöperating with said clip to bring the plates of the one pair to a frictional bearing against the plates of 5 the second pair and to maintain the heel and toe portions rigidly in their spaced relation.

4. A skate comprising heel and toe portions, a pair of spaced-apart extension plates having outwardly extending flanges 10 carried at one edge thereof formed to project from the heel portion in a forward direction, a pair of like flanged plates carried by the toe portion in a spaced-apart relation to be interfitted with the extension 15 plates of the heel portion with the flanges of the one set of plates overlying the flanges of the remaining set, a clip to be fitted over the interfitted extension plates to bear against the flanges of one set of plates, and 20 a clamp bolt coöperating with said clip to bring the flanges of the plates of one pair to a frictional bearing against the flanges of the plates of the second pair and to maintain the heel and toe portions rigidly in 25 their spaced relation.

5. A skate comprising heel and toe portions, a pair of spaced apart extension plates projecting forwardly from the heel portion and provided with outwardly extending flanges at the lower edges, a pair 30 of like flanged plates extending rearwardly from the toe portion in a spaced apart relation to be interfitted with the extension plates of the heel portion in a relation that 35 the flanges are fitted in an overlying arrangement, a U-shaped clip to be fitted over said extension plates to come to a bearing at its ends against the flanges of one set of plates, a washer to bear against the lower 40 sides of the flanges of the remaining set of plates, and a clamp bolt received through the clip and through the washer to clamp the parts in a relation that the flanges are brought to a frictional engagement to prevent 45 displacement of the parts from the adjusted relation.

6. A skate comprising heel and toe portions, a pair of spaced apart extension plates projecting forwardly from the heel portion 50 and provided with outwardly extending flanges at the lower edges, a pair of like flanged plates extending rearwardly from the toe portion in a spaced apart relation to be interfitted with the extension plates 55 of the heel portion in a relation that the flanges are fitted in an overlying arrangement, a U-shaped clip to be fitted over said

extension plates to come to a bearing at its ends against the flanges of one set of plates, a washer to bear against the lower sides of 60 the flanges of the remaining set of plates, a clamp bolt received through the clip and through the washer to clamp the parts in a relation that the flanges are brought to a frictional engagement to prevent displacement of the parts from the adjusted relation, and wheels carried by the heel and toe portions. 65

7. A skate comprising heel and toe portions, having adjustably interfitted extension members formed therewith to permit adjustment of the heel and toe portions to secure the desired extension of the skate, means to secure said adjustably interfitted extension members in the desired adjusted 75 relation, and portions formed in conjunction with said extension members to engage with the securing means to hold the extension members against endwise displacement in the adjusting movement. 80

8. A skate comprising heel and toe portions having spaced apart extension plates arranged to project therefrom in an interfitted relation to permit adjustment of the heel and toe portions to the desired relative 85 positioning, a clamp bolt mounted through said extension plates to be tightened thereagainst to hold the parts in the desired adjusted relation, and stops carried by said extension plates in laterally disposed relation to engage with said clamp bolt, to hold the extension plates against endwise displacement in the adjusting movement. 90

9. A skate comprising heel and toe portions, spaced apart extension members carried by said heel portion, spaced apart extension members carried by the toe portion to be adjustably interfitted with the extension members of the heel portion, a clamp bolt passed through the opening left by the 95 spacing apart of said members, a clip received over said clamp bolt to extend up along the sides of the extension members, and stop means connected with said extension members to abut against the bolt and 100 against the clip to hold said members against endwise displacement in the adjusting movement of the same.

In testimony whereof I affix my signature in presence of two witnesses.
